FIG. 9.

UNITED STATES PATENT OFFICE.

FRANK L. YOUNG, OF SAN ANTONIO, TEXAS.

MANHOLE-FORM.

1,400,927.

Specification of Letters Patent. Patented Dec. 20, 1921.

Application filed November 6, 1920. Serial No. 422,214.

To all whom it may concern:

Be it known that I, FRANK L. YOUNG, a citizen of the United States, and a resident of San Antonio, in the county of Bexar and 5 State of Texas, have invented certain new and useful Improvements in Manhole-Forms, of which the following is a specification.

My invention is an improvement in man hole forms, and has for its object to provide 10 a form for concrete structures, especially adapted for building man holes and other tubular bodies having restricted outlets, but also adapted for tubular bodies of any character, wherein the improved form 15 is composed of a series of sections so connected that they may be detached from each other to permit their removal through a restricted opening, and having means for expanding said sections to the desired diameter, and capable of being removed through 20 the restricted opening.

In the drawings:

Figure 1 is a vertical section of a man hole with the form in place,

25 Fig. 2 is a horizontal section through the form,

Fig. 3 is a perspective view of a unit of the upper reducing section,

30 Fig. 4 is a similar view of a unit of one of the lower or body sections,

Fig. 5 is a vertical section through a unit of the upper or reducing section,

Fig. 6 is a partial perspective view of one of the lower sections,

35 Fig. 7 is a plan view of another embodiment of the invention,

Fig. 8 is a vertical section of the same,

Fig. 9 is a horizontal section.

40 Fig. 10 is a sectional detail showing another method of forming the grooves.

In the embodiment of the invention shown in Figs. 1 to 5, the form is composed of an upper section and one or more lower sections. The lower sections are composed of 45 units of the character shown in Fig. 4. Each of these units is a plate or sheet 1 of sheet metal, of suitable gage, and at one side edge each unit is provided with a groove which is adapted to receive the other edge 50 of the succeeding unit.

This groove may be formed in any desired manner. As for instance, in Fig. 4, the side edge of the plate 1 is offset outwardly as indicated at 2, and a strip 3 of metal is secured to the body of the plate 1, extending beyond the body of the plate, but 55

not beyond the free edge of the outwardly offset portion 2. Thus there is provided a space between the strip 3 and the outwardly offset portion 2 of a width to receive the side 60 edge of the succeeding unit. Thus the units of a section may be connected together, there being provided registering openings, if desired, for receiving pins or the like to connect the units. 65

Each of the units with one exception, is provided with the groove 4 before mentioned, the said other unit having the outwardly offset portion 2, but not being provided with the strip 3, as clearly shown in 70 Fig. 2. This unit 1^a has an outwardly offset portion 2^a, and this laps over the side edge of the succeeding unit.

Thus each of the lower sections is built up from a series of similar units, and the 75 units of each series are of the same length, as may be of any convenient width, it being understood that the width does not exceed the diameter of the restricted opening through which the units must be removed 80 from the completed manhole.

Referring to Fig. 4, it will be seen that the free edge of the strip 3 does not extend as far as the free edge of the offset portion 2, and the extension of the offset portion 2 85 provides a guide for the entering into the groove 4 of the edge of the succeeding section. As many units may be provided in a course or section as may be desired, it being understood that the units are curved slightly 90 transversely on an arc whose center is the center of the man hole, and each section of units forms a cylindrical body.

The lowermost section differs slightly from the intermediate sections, in that certain of the units are notched as indicated at 5 to receive the conduit pipe 6, said notches being of a depth corresponding to approximately half the diameter of the pipe. Preferably four units of this series 100 are provided with notches, the units being arranged so that the pipes may extend at right angles with respect to each other.

The uppermost section differs from the other sections, in that it is a reducing section. 105 As shown in Fig. 3, each of the units 7 is of greatest width at its bottom and tapers toward its top, and the ends of the unit are bent to lie at an obtuse angle with respect to the body, and to extend approximately parallel 110 to the body, as clearly shown at 8 and 9 in Fig. 3.

One side edge of each unit is offset out-

wardly as indicated at 10, and all of the units but one have secured to the edge thereof at the said outwardly offset portion a strip 11, corresponding to the strip 3 of Fig. 4, and 5 similarly arranged. This strip and the outwardly offset portion provide a groove 12 similar to the groove 4 for receiving the side edge of the succeeding unit.

One of the units has no strip 11, but does 10 have the outwardly offset portion for lapsing on the adjacent unit. The units are held in expanded condition by means of the expanding rings shown in Figs. 1 and 2. Each 15 of these rings consists of two similar sections 13, and the sections have at their ends inwardly extending lugs 14.

These lugs have registering openings, and bolts 15 are passed through the openings.

The bolts are threaded at each end, and each 20 bolt is engaged by nuts 16 on each side of each lug 14. By means of the nuts 16, the lugs may be forced away from each other to expand the rings 13 to hold the sections properly expanded.

25 In setting up the improved form, each series of units is arranged with its lower end within the upper end of the preceding series, and an expansion ring is placed at each joint, inside the form. In order to prevent spreading of the units of a series, each series is encircled by a series of flexible members 17 of ring formation, the said members being wires, ropes or the like, and formed from pieces having their ends connected.

30 As shown in Fig. 1, a flexible member 17 is arranged about the lowermost series at the bottom of the form. Another is arranged at a point between the lower and the intermediate series, and other members are arranged about the intermediate series, one 35 near the top and one intermediate the ends. An expansion ring is placed at each joint, and a smaller ring is placed at the top of the uppermost section, that is, at the point where 40 the portions 8 of the units join.

The uppermost reducing section is also held by encircling flexible members. These 45 flexible members may be left in the man hole after the concrete has been poured if desired, or they may be removed if thought best. In practice, the hole for the man hole is dug. The form is then set up, and the concrete is poured. After the concrete has set, the units 50 are removed, the sectional rings being first released. It will be obvious that when the ring at the top and that at the bottom of the upper series of sections is removed, that unit whose edge is not received in a groove may be moved inwardly and disengaged from the preceding unit. Thus the units may be removed in sequence and withdrawn through the restricted opening.

55 Afterward the units of the other sections are withdrawn, one at a time, until the entire form has been removed. In setting up the

form, it is advisable sometimes to have a stop on each section for limiting the downward movement of the succeeding section. This stop may be in the form of a clamping ring encircling the series, and having means 70 for clamping the ends together, or it may be a flexible member. After the expansion rings are once expanded, nothing is needed to hold the sections in proper position.

In practice, eight or more units are provided in each section. The units of the lower section may, if desired, be arranged as shown in Fig. 6. In this arrangement the units 18 have one side slit near the top and bottom as shown, to form tongues 19 at the top and bottom of one side edge of the unit. That portion of the side edge between the slits is offset outwardly as shown at 20, and the tongues 19 are offset inwardly.

When now the sections are joined, the 85 tongues 19 are placed upon each other, and the offset portion 20 laps on the adjacent portion 21 on the opposite side to the tongues 19. The parts are thus held from slipping with respect to each other, and are held in properly spaced relation. It will be understood that in the construction of Fig. 6, one section has no tongue 19, having merely the outwardly offset portion 20 which may extend the full length of the unit. The expansion 90 rings are arranged at the tongues 19.

In Figs. 7 to 9 there is shown a construction having different cross sectional form. In this arrangement the man hole is oblong or elliptical. The units 21 are the same as 100 those shown in Fig. 3, each having one side edge outwardly offset as shown at 22, to receive the adjacent edge of the succeeding unit. The units having the strips 23 corresponding to the strips 3, the said strips 23 are 105 riveted to the units to form between them and the outwardly offset portions grooves for receiving the edges of the succeeding units.

Expansion rings 24 are provided, similar to the rings 13, but so shaped that they each 110 fit within the form, and these rings are expanded by bolts 25 and nuts 26, in the same manner as the rings 13 are expanded. The bolts engage inwardly extending lugs 27 on the ring sections. As shown in Fig. 8, three 115 sections are provided, namely a lower section, an intermediate section, and an upper section, the upper section being the reducing section.

It will be obvious that as many sections 120 may be used as may be necessary, as for instance, one or many. The units of the lower course may be suitably notched to receive pipes, and it is obvious that the units of any other course might have openings if desired 125 for the same purpose.

In Fig. 10 there is shown a construction wherein the units 28 have strips 29 riveted to their side edges to provide grooves between the said strips. This construction is 130

the same as that shown in Fig. 3 with the exception that there is no offset portion of the unit, the edge of the succeeding unit being received directly between the strips.

5 It will be obvious that instead of providing the double seam at the connection of the portions 8 and 9 with the body of the units 7, such seams might be omitted. These seams are provided for strengthening. The 10 form is composed of sections, each of which is composed of a series of units, interlocking at their side edges in such manner that they may be disassembled by moving them inward, and thus may be removed through a 15 restricted opening, together with the expanding rings for holding them expanded.

I claim:

1. A form for hollow structures of plastic material with restricted outlets, comprising 20 courses of units, the units of each series being so shaped that when their side edges are lapped they will conform to the cross sectional shape of the structure, and the units of one series being shaped to correspond 25 with the cross sectional shape of the outlet, expansion rings within the units of the series for holding them from collapsing, the units of each series fitting at their lower ends within the upper ends of the units of the 30 next lower series, and flexible bands encircling the units of the series to hold them against the rings, the units of each series having interlocking mechanism at their side edges for limiting the movement of the units 35 on each other, said mechanism being omitted from one of the units for the purpose specified.

2. A form for hollow structures of plastic material with restricted outlets, comprising 40 courses of units, the units of each series being so shaped that when their side edges are lapped they will conform to the cross sectional shape of the structure, expansion rings within the units of the series for holding 45 them from collapsing, the units of each series fitting at their lower ends within the upper ends of the units of the next lower series, and flexible bands encircling the units of the series to hold them against the rings.

50 3. A form for hollow structures of plastic material, comprising tubular tiers or units, the units of each tier so shaped that when their side edges are lapped they will conform to the cross sectional shape of the structure, 55 the units of each tier fitting at their lower ends within the upper ends of the units of the next lower tier, and expansion rings within the tiers at their ends, whereby pressure at the joint between the units of succeeding tiers holds the tiers from collapsing.

60 4. A form for hollow structures of plastic material with restricted outlets, comprising courses of units, the units of each series being so shaped that when their side edges are

lapped they will conform to the cross sectional shape of the structure, expansion rings within the units of the series for holding them from collapsing, the units of each series fitting at their lower ends within the upper ends of the units of the next lower 70 series, and flexible bands encircling the units of the series to hold them against the rings, the units of each series having interlocking mechanism at their side edges for limiting the movement of the units on each other, 75 said mechanism being omitted from one of the units, for the purpose specified.

5. A form for hollow structures of plastic material, with restricted outlets comprising courses of units, and expanding rings for 80 the units about which the units are arranged, said rings having means for expanding the same to the required cross section, and each unit having one side edge offset outwardly to receive the adjacent side 85 edge of the succeeding unit, and to provide a structure between the offset portion and the body of the unit against which the edge of the other unit may abut.

6. A form for hollow structures of plastic 90 material with restricted outlets comprising courses of units, and expanding rings for the units about which the units are arranged, said rings having means for expanding the same to the required cross section, 95 and means encircling the units for limiting the expanding movement thereof.

7. A form for hollow structures of plastic material with restricted outlets comprising 100 courses of units, and expanding rings for the units about which the units are arranged, said rings having means for expanding the same to the required cross section.

8. A form for hollow structures of plastic material with restricted outlets comprising 105 courses of units, and expanding rings for the units about which the units are arranged, said rings having means for expanding the same to the required cross section, and each unit having one side edge offset outwardly 110 to receive the adjacent side edge of the succeeding unit, and to provide a structure between the offset portion and the body of the unit against which the edge of the other unit may abut, each unit having means at the 115 outwardly offset portion for engaging the inner face of the adjacent unit to hold it from inward movement.

9. A form for hollow structures of plastic material with restricted outlets, comprising 120 a course of units so shaped that when their side edges are lapped they will conform to the cross sectional shape of the structure, and expansion rings within the series for holding the units in expanded condition, and 125 flexible members encircling the units to hold them against the expansion rings.

FRANK L. YOUNG.
